FEEDING DEVICE

Filed Feb. 11, 1930

UNITED STATES PATENT OFFICE

WILLIAM A. SMITH, SR., OF EASTON, PENNSYLVANIA, ASSIGNOR TO INGERSOLL-RAND COMPANY, OF JERSEY CITY, NEW JERSEY, A CORPORATION OF NEW JERSEY

FEEDING DEVICE

Application filed February 11, 1930. Serial No. 427,517.

This invention relates to feeding devices, but more particularly to a device of this character adapted for actuating a percussive motor relatively to its support.

One object of the invention is to utilize the force of the reciprocating piston of the motor for moving the motor relatively to the support.

Another object is to prevent recoil of the motor upon the reversal of the piston at the end of one stroke and to enable the motor to be moved along the support by the jar imparted by the piston upon the reversal of the piston at the end of the opposite stroke.

Other objects will be in part obvious and in part pointed out hereinafter.

In the accompanying drawings illustrating the invention and in which similar reference characters refer to similar parts,

Figure 1 is a plan view of a portion of the motor and its support having the invention applied thereto,

Figure 2 is an elevation, partly in section, taken through Figure 1 on the line 2—2 looking in the direction indicated by the arrows,

Figure 3 is an elevation, partly in section, taken through Figure 2 on the line 3—3 looking in the direction indicated by the arrows, and

Figure 4 is an elevation, partly in section, taken through Figure 1 on the line 4—4 looking in the direction indicated by the arrows.

Referring more particularly to the drawings, A designates a motor which, in this instance, is illustrated as a portion of a rock drill, and B is a support whereon the motor A may be slidably mounted to enable the said motor to be advanced to the work and retracted therefrom.

The motor A comprises the usual cylinder B' adapted to accommodate a piston C of the reciprocating hammer type usually employed for delivering blows of impact to a working implement, such as a drill steel (not shown).

Secured to the rear end of the cylinder B', as by means of side rods or bolts D, is a back head E to form a closure for the rear end of the cylinder B' and to form a housing for a throttle valve F whereby the admission of pressure fluid into the motor A may be con-

trolled. The motor A may be provided with suitable valve mechanism (not shown) for automatically effecting the distribution of pressure fluid to the cylinder B'.

In accordance with the present invention, means are provided for enabling the motor A to be moved longitudinally of the support B by the jar imparted to the motor by the piston C upon the reversal of the said piston at the ends of its strokes. The means provided for this purpose comprises a stationary or fixed member in the form of a rod G which may be suitably supported at its ends by the support B.

The rear end of the rod G is preferably secured to a cross head H which in turn is supported by standards J extending rearwardly of the support B. The standards J may be in the form of bolts secured to the rear end of the support B and having sleeves K thereon which abut the support B and the cross head H for holding the said cross head in spaced relation with respect to the support B.

Secured to the back head E as by means of the side rods D is a bracket L whereon is pivotally mounted a friction shoe O. The friction shoe O is adapted to be moved into different positions of frictional engagement with the rod G and is preferably arranged approximately laterally with respect to the rod G. In the end of the friction shoe adjacent the rod G is a groove P of a shape to conform substantially to the surface of the rod G. When used in connection with a cylindrical rod, such as that illustrated, the groove P may be of partly circular form and the rear and front edges Q and R respectively of the groove P constitute gripping edges which, in certain positions of the friction shoe O, engage the rod G.

In order to actuate the friction shoe into frictional engagement with the rod G, the bracket L is provided with a pair of cylinders S and T disposed forwardly and rearwardly respectively of the friction shoe O. The cylinders S and T may be secured to the bracket in any suitable manner, as for instance, by bolts U, and are provided with chambers V to accommodate plungers W and X, the plunger

W being disposed within the cylinder S and the plunger X in the cylinder T.

The movement of the plungers W and X is affected by means of pressure fluid and such

5 pressure fluid is conveyed to the outer or closed ends of the cylinders by inlet passages Y which communicate with a valve chamber Z in a valve chest b attached to the side of the bracket L and secured thereto by bolts c.

10 Within the valve chamber Z is a throttle valve d in the shape of a tapered plug, one end of which extends exteriorly of the valve chest b to receive a wing lever e whereby the throttle valve d may be manipulated.

15 The throttle valve d has a recess f in its inner end to which pressure fluid is supplied by a supply passage L' which is formed in the bracket L and is controlled by the throttle valve F. In the wall of the throttle valve d is a port g which communicates with the recess f and is adapted to register with the supply passages Y.

20 In the periphery of the throttle valve d is a groove k to establish communication between the port g and the supply passages. The groove k is of such extent that it may only afford communication between the port g and one or the other of the supply passages Y. In the same transverse plane as the groove 25 k is a second groove o which is of such extent that it may simultaneously establish communication between both of the supply passages Y and an exhaust port p in the valve chest b and leading to the atmosphere.

30 35 To the end that the rod G may be suitably supported intermediate its ends and more particularly at the point at which the friction shoe O acts against the said rod, the bracket L is provided with a suitable bearing portion q which has a bore r through which the rod G extends. The bore r may, as shown, be of larger diameter than the rod T to receive a bushing s which serves as a renewable bearing surface for the rod G. The bore t within the bushing s is only of 40 sufficiently larger diameter than the rod G to permit said bushing to pass freely over the surface of the rod without causing undue friction between these elements.

45 50 The bushing s may be secured in the assembled position in any suitable manner, as for instance, by means of a nut u which is threaded on a rearwardly projecting end v of the bushing and acts against the corresponding end of the bearing q. On the front end of the bushing s is a head w which seats against the front end of the bearing q.

55 The operation of the device is as follows: Let it be assumed that the motor A is in operation so that the hammer piston D delivers its blows to the working implement intended to be actuated. When the motor A is thus operating it is, of course, essential that it be actuated longitudinally of the support B in the direction of the work so that

the full force of the hammer piston may be effectively applied to the working implement for driving the said working implement into the work.

60 In order to constantly maintain the motor in the correct operative position with respect to the working implement, the friction shoe O should occupy a position substantially like that illustrated in Figure 2 in which the gripping edge Q bears against the rod G. To the end that the friction shoe O may be maintained in this position, the throttle valve d is rotated so that pressure fluid may flow through the rear supply passage Y into the piston chamber V of the cylinder T.

65 Pressure fluid thus admitted will act against the plunger X to rock the friction shoe O forwardly so that when the hammer piston C reverses its direction at the end of its rearward stroke, the jar resulting from such reversal will cause the gripping edge Q to tightly grip the rod G. The motor A will therefore be prevented from recoiling from the work.

70 As the piston C reaches the end of its forward stroke, the jar resulting from the act of reversal of the piston will carry the motor A forwardly along the support B for a slight distance depending upon the degree 75 of penetration of the working implement into the work. From this point on the cycle of operations may be repeated. Upon each forward stroke of the piston C, the motor A will be advanced a slight distance so that the said motor may at all times be maintained in the proper operative position for assuring the maximum effect of the blows 80 of the hammer piston C, and during each rearward stroke of the piston C, the motor A will be held against recoil by the gripping edge Q of the friction shoe O. In other words, the gripping edge Q will alternately grip and release the rod G, the effect of this action of the friction shoe O being that the motor A will be gradually advanced towards the work at a speed which will assure the best drilling results.

85 90 When the motor A approaches the foremost limit of its travel with respect to the support B, the throttle valve d may be rotated to a position for admitting pressure fluid into the piston chamber V of the cylinder S. In this position of the throttle valve the piston chamber V of the cylinder T will be in communication with the atmosphere through the supply passage Y, the groove o and the exhaust port p so that the plunger X may readily be retracted in its piston chamber. The pressure fluid admitted into the cylinder S will then act against the plunger W to reverse the position of the friction shoe O.

95 100 In the new position of the friction shoe O the gripping edge R will seat upon the rod G. Meanwhile the hammer piston C may con- 105

tinue its reciprocations. By reversing the friction shoe O in the manner described, only the jar resulting upon reversal of the piston C at the rearward end of its stroke will be effective for moving the motor A in a rearwardly direction. Upon reversal of the piston C in the front end of the cylinder B', the motor A will be prevented from recoiling by the gripping edge R.

10 The jars imparted by the hammer piston to the motor will tend only to move the motor A rearwardly. After the motor has reached its rearward travel on the support, the throttle valve d may be rotated to a position in which the groove o will establish communication between both supply passages Y and the exhaust port p. At the same time the throttle valve d may be closed to both cut off the supply of pressure fluid to the motor A and also to cut 20 off the flow of pressure fluid to the passage L'.

As will be readily apparent, by placing the throttle valve d in the neutral position illustrated in Figure 4 in which only atmospheric pressure exists in both the cylinders S and T 25 the friction shoe O is permitted to also assume a neutral position in which neither of the gripping edges R or Q will be effective to interfere with the free movement of the motor A on its support. This is desirable in 30 many instances, particularly when drilling horizontal holes, for the reason that it enables the motor to be readily moved along its support by the operator.

The present invention has been found to be 35 unusually efficient in practice. This is due largely to the fact that the percussive elements, such as the motor A, may at all times be maintained in the proper operative position with respect to the implement which it is 40 intended to actuate. A maximum effect of the blows of the hammer piston will therefore be obtained.

Another very desirable feature of the present invention is that while the feeding means 45 assures a proper advancement of the motor relatively to its support, it does not actuate the motor in the direction of the work with such undue force as to interfere with the proper operation of the motor, particularly 50 in the case of rock drills of the drifter type having rotation mechanism for rotating the working implement.

I claim:

55 1. In a feeding device, the combination with a motor and a support whereon said motor is slidably mounted, a reciprocatory hammer piston in the motor imparting jars thereto for moving the motor longitudinally of the support, of relatively movable cooperating frictional members associated with the motor and the support to prevent recoil of the motor, and pressure fluid actuated means for pressing one of the members into frictional 60 engagement with the other member to enable

the hammer piston to advance and retract the motor relatively to the support.

2. In a feeding device, the combination with a motor and a support whereon said motor is slidably mounted, a reciprocatory hammer piston in the motor imparting jars thereto tending to move the motor longitudinally of the support, of a fixed member, means adapted to engage the fixed member, and pressure fluid actuated means for actuating the first said means into frictional engagement with the fixed member, thereby preventing recoil of the motor upon reversal of the piston at the end of one stroke and permitting the motor to be moved along the support by the piston upon reversal of the piston at the end of its opposite stroke.

3. In a feeding device, the combination with a motor and a support whereon said motor is slidably mounted, a reciprocatory hammer piston in the motor imparting jars thereto for moving the motor longitudinally of the support, of a stationary member extending longitudinally of the support, a movable member carried by the motor and adapted to frictionally engage the stationary member for preventing recoil of the motor, and pressure fluid actuated means to press the movable member selectively into different positions for frictionally engaging the stationary member, thereby enabling the hammer piston to advance and retract the motor relatively to the support.

4. In a feeding device, the combination with a motor and a support whereon said motor is slidably mounted, a reciprocatory hammer piston in the motor imparting jars thereto for moving the motor longitudinally of the support, of a fixed member, friction means movable relatively to and adapted to engage the fixed member, a plurality of pressure fluid actuated means acting on opposite sides of the friction means for actuating the said friction means into different engaging positions, and a valve for controlling the flow of pressure fluid to the pressure actuated means.

5. In a feeding device, the combination with a motor and a support whereon said motor is slidably mounted, a reciprocatory hammer piston in the motor imparting jars thereto for moving the motor longitudinally of the support, of a rod affixed to the support, a friction shoe carried by the motor and adapted to frictionally engage the rod for preventing recoil of the motor, fluid actuated plungers acting on opposite sides of the friction shoe for actuating said friction shoe into different engaging positions, and a valve for selectively controlling the flow of pressure fluid to and from the plungers.

6. In a feeding device, the combination with a motor and a support whereon said motor is slidably mounted, a reciprocatory hammer piston in the motor imparting jars

- thereto for actuating the motor longitudinally of the support, of a stationary rod extending longitudinally of the support, a friction shoe pivotally connected to the motor and adapted to frictionally engage the rod for preventing recoil of the motor, fluid actuated plungers adapted to act selectively against opposite sides of the friction shoe to press said friction shoe into different positions for engaging the rod, thereby enabling the hammer piston to advance and retract the motor relatively to the support, and a valve for controlling the flow of pressure fluid to and from the plungers.
7. In a feeding device, the combination with a motor and a support whereon said motor is slidably mounted, a reciprocatory hammer piston in the motor imparting jars thereto for actuating said motor relatively to the support, of a stationary rod extending longitudinally of the support, a bracket carried by the motor and having a bore through which the rod extends, a friction shoe pivoted on the bracket for frictionally engaging the rod, cylinders on the bracket and arranged on opposite sides of the friction shoe, plungers in the cylinders for pressing the friction shoe into different positions of engagement with the rod for preventing recoil of the motor, thereby enabling the motor to be advanced and retracted on the support by the piston, passages in the bracket for conveying pressure fluid from a source to the cylinders, and a valve for controlling the passages to selectively admit pressure fluid into the cylinders.
8. In a feeding device, the combination with a motor and a support whereon said motor is slidably mounted, a reciprocatory hammer piston in the motor imparting jars thereto for actuating said motor relatively to the support, of a rod supported at its ends by the support and extending longitudinally thereof, a bracket carried by the motor, a bushing carried by the bracket and forming a movable support for the rod intermediate the ends of the rod, a friction shoe pivoted on the bracket for frictionally engaging the rod, cylinders on the bracket and disposed on the opposite sides of the friction shoe, plungers in the cylinder for pressing the friction shoe into different positions of engagement with the rod to prevent recoil of the motor, thereby enabling the motor to be advanced and retracted on the support by the piston, passages in the bracket for conveying pressure fluid to the cylinders to actuate the plungers, and a throttle valve for selectively controlling the flow of pressure fluid to and from the cylinders.

In testimony whereof I have signed this specification.

WILLIAM A. SMITH, SR.
